FIG. 3

FIG. 4.

UNITED STATES PATENT OFFICE.

BENJAMIN CALVEN BARTLEBAUGH, OF WHEELING, WEST VIRGINIA.

GAS-STOVE.

1,166,313.

Specification of Letters Patent. Patented Dec. 28, 1915.

Application filed January 11, 1915. Serial No. 1,614.

To all whom it may concern:

Be it known that I, BENJAMIN C. BARTLEBAUGH, a citizen of the United States, residing at Wheeling, in the county of Ohio and State of West Virginia, have invented 5 certain new and useful Improvements in Gas-Stoves; and I do declare the following to be a full, clear, and exact description of the invention, such as will enable others skilled in the art to which it appertains to 10 make and use the same.

This invention relates to improvements in gas heating stoves or furnaces.

The object of the invention is to provide a 15 stove of this class so constructed that perfect combustion will be insured, thereby producing a maximum amount of heat with a minimum consumption of gas and which also consumes all the moisture and poison in the 20 gas, thus avoiding all danger of monoxid gas poisoning.

Another object is to construct a stove of this character so that the air and gas which passes out through the burner will be thoroughly heated and dried.

Another object is to provide a gas stove 25 with a channel at the back for carrying off the odors and having means for creating draft or suction through said channel and means for directing the odors back into the fire.

Another object is to provide a burner having outlets for the fuel, so arranged that a maximum amount of air is fed to the body 35 of the fire, thereby producing a thick flame which retains all the poison in the gas and consumes it without permitting any to pass off to the atmosphere.

With these and other objects in view, the 40 invention consists of certain novel features of construction, and the combination and arrangement of parts as will be more fully described and claimed.

In the accompanying drawings: Figure 1 45 represents a transverse vertical section taken on the line 1—1 of Fig. 2; Fig. 2 is a longitudinal vertical section taken on the line 2—2 of Fig. 1; Fig. 3 is a horizontal section taken on the line 3—3 of Fig. 1; Fig. 4 is a 50 similar view taken on the line 4—4 of Fig. 1; Fig. 5 is a detail vertical section taken on the line 5—5 of Fig. 1.

In the embodiment illustrated, a shell or casing 1 of any desired size and form is 55 shown which is made air-tight throughout except at its bottom and front where open-

ings are provided for the intake of air to aid in combustion.

An upright partition 2 is spaced from the rear wall 3 of the casing 1 and terminates 60 near the top and bottom thereof to form a channel 4 for the passage therethrough of the current of heated air and the obnoxious odors from the gas which are carried under and around the burner to be described for 65 the purpose of heating and drying the fuel in the burner in order that a mixture of hot dry gas and air may be fed through the burner openings for ignition. This partition 2 has a V-shaped recess in its upper 70 edge, which is designed for creating suction or draft in the channel at the rear of said partition, an entraining action being brought about by the air entering below the plate 9 and mingling with the products of combustion 75 and passing over the upper edge of the partition 2.

The front wall 5 of the casing has an air inlet opening 6 extending transversely thereacross intermediately of its ends, preferably at a point about midway the height thereof and the lower wall of said opening is rolled outwardly to form a reinforcing lip 7. A transversely curved shield 8 is secured at one edge to the front wall 5 of the casing 80 on its inner face below the lower wall of the opening 6 therein with its concave face disposed inwardly and extending adjacent the burner to be described for directing the products of combustion and odors back into 85 the flame.

A plate 9 is secured at its sides to the end walls of the casing with its lower edge arranged immediately between the upper and lower end of the opening 6 in said front wall. 90 The upper wall of said opening is deflected outwardly and is provided with a hood 11 whereby a mouth is formed between it and the lower edge or end of the plate 9. This plate or partition 9 is inclined upwardly 100 and inwardly with its upper end engaging the top of the casing 1 in advance of the upper edge of the partition 2, forming a restricted throat at this point which facilitates the suction of the air drawn through the V-shaped recess. This plate 9 performs the double function of a deflector for the obnoxious gases for directing them over the partition, and as a partition to separate these gases which are retained in the combustion chamber from the chamber 105 formed between said plate 9 and the walls

of the casing in advance thereof. As shown, the plate 9 is provided at its opposite side edges with right angularly disposed flanges 9' which are attached to the end walls of the casing by suitable fastening elements (see Fig. 1). The odors and other materials in the heated air being deflected by said plate 9, over into the channel 4 at the rear of the stove and are conducted back to the flame where they are consumed.

A burner 12 is mounted in the lower half of the casing 1 with the gas discharge openings 13 thereof disposed opposite the lower wall of the front opening 6. This burner 12 is in the form of a cylinder of a length corresponding to the width of the casing 1 and of a diameter less than the depth or thickness of said casing. This cylinder 12 is closed at both ends and is designed to be supported in the casing between the curved shield 8 and the partition 2 at the rear of the casing by any suitable means with the gas discharge openings 13 therein arranged substantially flush with the lower end of the opening 6, in order that air admitted through said opening may be mixed with the gas passing out of the burner openings to provide a more perfect combustion.

By constructing the stove casing with the comparatively small opening in the front wall thereof, and arranging the deflecting plate 9 and burner in the manner shown and described, sufficient fresh air is admitted through the opening 6 and the open bottom to support combustion, and the deflecting plate directs the products of combustion rearwardly over the partition 2 so that there is no danger of the obnoxious gases passing out into the surrounding atmosphere, said gases being directed back to the burner and consumed. Moreover, by the positioning of the plate 9 with its lower end disposed near the center of the casing front wall and its upper end engaging the top near the rear thereof and adjacent the partition 2, an enlarged combustion chamber is formed above the burner tapering toward its discharge end so that the products of combustion are retained therein a sufficient time to substantially exhaust their heating capacity before they pass through the restricted discharge at the tapered end of said chamber, thereby greatly increasing the heating power of the stove. This arrangement of the plate 9 also provides an auxiliary heating chamber 10, the heat radiating from said plate serving to heat the air in the chamber 10 which heats the walls of the chamber 10 said walls radiating the heat therefrom to the surrounding atmosphere.

The discharge openings 13 for the gas are formed in the upper face of this cylinder 12 in a plurality of series which extend longitudinally of the cylinder and which series

are spaced laterally to permit the free passage of air between the respective series. As shown, three series of inlet openings 13 are provided and each comprises a multiplicity of fine perforations and the spaces between these series permits the air admitted through the opening 6 to combine with the gas while burning, the air being supplied on each side of each series of openings and thereby feeding six times the amount of air to the body of fire, as is fed by one row of outlets or openings which produces a flame of maximum heating capacity with a minimum consumption of gas.

The cylinder 12 is provided in its side opposite the discharge openings, with a plurality of longitudinally extending spaced cone-shaped inlets 14 for receiving gas at different points and passing it into the cylinder, whereby a better and a quicker mixing of the gas and air in the burner is provided and which also provides for the entrance into said cylinder of a great volume of air to aid in combustion. This cylinder 12 has a longitudinally extending horizontally disposed partition 12' secured therein below the discharge openings 13 thereof, with its ends spaced from the ends of the cylinder to provide for the passage around said ends of the mixed air and gas, which is designed to pass out through the openings 13, said air and gas having first been heated and dried in the cylinder below the partition 12'.

A gas distributing chamber or casing 15 is disposed in the lower portion of the stove below the cylinder 12 and may be of any suitable or desired shape, being here shown substantially triangular in form with a gas inlet opening 16 in the larger end wall thereof, having a supply pipe 17 secured therein and extending outwardly through the front wall of the casing and provided with a nipple 18 for connection with a hose or other supply pipe (not shown).

A plurality of gas discharge pipes 19 extend laterally from the apex and sides of the triangular casing or chamber 15 and are disposed in a plane out of alignment with the inlet opening 16 thereof, in order that the force of the gas entering through the supply pipe may be broken up in the chamber before discharging it through the pipes 19. Each of these pipes 19 is provided with a nipple 20 extending upwardly at right angles to the body of the pipe and provided with a small discharge aperture 21, and which are positioned to open into the cones 14 of the cylinder 12 and thus provide for the entrance of a strong stream of gas into the burner which commingles with the air fed in the cones 14 and forms a perfect mixture for ignition.

By constructing a gas stove or furnace in the manner above described combining therewith the particular distributing cham-

ber specified, the gas leaving the cylinder 12 is burned in a flame which retains and consumes all the obnoxious poisons in the gas and prevents them from passing off into 5 the atmosphere, thereby rendering the stove perfectly safe for use, there being no possibility of monoxid gas poisoning.

The flame referred to is a thickened flame produced by the great quantity of air which 10 is mixed with the gas as it passes into the burner and the air mixed with the gas passing out of the burner owing to the peculiar arrangement of discharge openings for the gas with spaces between them so that air is 15 fed between the flames or rows of fire on top of the burner. By the peculiar construction of the burner described herein three times as much air is fed into the burner with the gas as is fed by the ordinary 20 burner and three times the amount of air is fed to the flame while burning. This feeding of air with the gas and to the flame produces a thick body of fire on top of the burner that looks like quivering hot lead 25 and not a thin sheet of flame as is produced by other burners.

I claim as my invention:

1. In a gas stove, the combination of a rectangular casing closed air-tight except at 30 its bottom and front, the front wall thereof being closed except for an opening at its center, extending transversely thereacross, said front wall being deflected outwardly adjacent the upper end of said opening, a 35 transversely curved inwardly extending shield mounted on the front wall below and adjacent to said opening with its inturned free end disposed in horizontal alinement with the lower edge of the opening in front 40 of the casing, an upright partition extending from end to end of said casing adjacent to and spaced from the rear wall thereof and terminating at its upper end adjacent to but spaced from the top of the casing, a 45 burner mounted between said partition and shield and spaced from both, the lower end of said upright partition being arranged below the burner outlet, and an obliquely disposed deflecting and separating plate ex- 50 tending across the upper end of said casing

from end wall to end wall thereof, with its upper end engaging the top of the casing in a plane in advance of but adjacent to the plane occupied by the upper end of said upright partition to form a restricted discharge throat between them extending from end to end of the casing, the lower end of said deflecting plate being positioned at the front of the casing substantially in alinement with the free edge of the deflected portion of the front wall above the opening therein and forming an air-heating chamber in the upper front corner of said casing, having a mouth at its lower end, the body 60 of said deflecting plate being disposed above said burner in vertical alinement therewith with its upper and lower edges extended laterally into planes beyond the planes occupied by the side walls of the burner, and operating to deflect the products of combustion over the rear partition and to separate them from the air heating chamber in advance of said plate, said deflector plate and upright partition forming a chamber extending approximately from the burner to 70 the top of the casing and tapering toward its upper end whereby the products of combustion are retained therein a sufficient time to exhaust their heating capacity and radiate a maximum amount of heat through the 80 casing walls before being directed through the restricted discharge opening to the space at the rear of the casing.

2. A gas stove comprising a casing, a partition mounted in said casing adjacent the 85 rear wall thereof and spaced therefrom, said partition having a V-shaped opening at its upper end, a burner disposed in said casing, and means for deflecting the impurities in the heated air over said partition into the space behind it from which it is directed back to the burner.

In testimony whereof I have hereunto set my hand in presence of two subscribing witnesses.
